UNITED STATES PATENT OFFICE.

ISAC O. CARLSON, OF CHICAGO, ILLINOIS.

ICE-CHEST SHELF.

1,218,166.

Specification of Letters Patent.

Patented Mar. 6, 1917.

Application filed August 17, 1914. Serial No. 857,197.

To all whom it may concern:

Be it known that I, ISAC O. CARLSON, a citizen of the United States, and a resident of the city of Chicago, county of Cook, and

5 State of Illinois, have invented certain new and useful Improvements in Ice-Chest Shelves, of which the following is a specification.

10 My invention relates to improvements in shelves for ice chests and has for its object the provision of an improved shelf of this character so constructed as to facilitate the insertion of vertically elongated articles such as milk and other bottles in the ice chest.

15 The invention consists in the combinations and arrangements of parts hereinafter described and claimed.

The invention will be best understood by reference to the accompanying drawing forming a part of this specification, and in which—

20 Figure 1 is a perspective view of the front of an ice chest showing a shelf embodying my invention in position of use, and

25 Fig. 2, an enlarged top plan view of the shelf.

The preferred form of construction as illustrated in the drawing comprises a substantially rectangular frame formed from a single rod 3 bent to form both sides, the rear and the larger portion of the front of said frame but terminating at a point some distance from one side of said frame so as to leave a gap 4 therein, the end of said rod at the inner corner of said gap being bent downwardly to form a supporting leg 5 adapted to rest upon the bottom of the ice chest and constitute a support for the corresponding portion of the frame. A reinforcing rod 6 is extended from the front to the rear of said frame adjacent the inner side of said gap and wires 7 are extended between the reinforcing rod 6 and the corresponding portion of the frame to form a supporting shelf in the usual manner.

40 The shelf is inserted as the lower shelf of the ice chest in the usual manner, the sides thereof being supported on inwardly projecting pins 8 in the ice chest or other suitable means of support. The length of the supporting leg is such that it rests upon the bottom of the ice chest thus constituting a corresponding support for a corner of the shelf. By this arrangement it will be observed that vertically elongated articles such

as milk or other bottles may be readily inserted in the ice chest, the tops thereof extending through the gap thus formed in the shelf.

While I have illustrated and described the preferred form of construction for carrying my invention into effect, this is capable of variation and modification without departing from the spirit of the invention. I therefore, do not wish to be limited to the precise details of construction set forth, but desire to avail myself of such variations and modifications as come within the scope of the appended claims.

Having described my invention what I claim as new and desire to secure by Letters Patent is:

1. An ice chest including the end walls equipped with shelf supporting means, in combination with a shelf of appreciably less length than the distance between said end walls, an extension on the rear of said shelf complementing the same to the full width between said walls and adapted to rest upon the adjacent supporting members, and a leg on the forward corner of the end provided with said extension, substantially as described.

2. An ice chest including the end walls equipped with shelf supporting means, in combination with a shelf comprising a frame of appreciably less length than the distance between said end walls and a body portion supported thereon, an extension on the rear of said shelf complementing the same to the full width between said walls and adapted to rest upon the adjacent supporting members, and a leg on the forward corner of the end provided with said extension, substantially as described.

3. An ice chest including the end walls equipped with shelf supporting means, in combination with a shelf comprising a frame of appreciably less length than the distance between said end walls and a body portion supported thereon, the rear member of said frame being extended to the full width and then bent forward to rest upon the adjacent supporting members, and a leg on the forward corner of the end provided with said extension, substantially as described.

4. A shelf for an ice chest comprising a substantially rectangular frame made from a single rod bent to form both sides, the rear and a portion of the front of said

11

frame, but leaving a gap in the front of said frame adjacent one side thereof, the end of the rod at the inner corner of said gap being bent downwardly to form a supporting leg adapted to rest upon the bottom of an ice chest; a reinforcing rod connecting the front and rear portions of said frame at the side of said gap; and a wire mesh supported on said reinforcing rod and the correspond-

ing portions of said frame, substantially as 10 described.

In testimony whereof I have signed my name to this specification in the presence of two subscribing witnesses.

ISAC O. CARLSON.

Witnesses:

JOSHUA R. H. POTTS,
HELEN F. LILLIS.
